UNITED STATES PATENT OFFICE.

BENJAMIN W. SUCKLE AND THOMAS J. MATHEWS, OF PHILADELPHIA, PENNSYLVANIA.

THREE-CIRCUIT LOW-LOSS TUNER.

Application filed September 10, 1924. Serial No. 736,956.

This invention has reference to tuning devices for radio or wireless telegraphs.

In radio receiving sets generally, and more particularly in the less expensive sets, great difficulty is encountered in the reception from stations at a great distance and frequently difficulty is encountered even when receiving from stations close by. This difficulty is due, among other things, to a lack of sharp capabilities in the parts of such sets, and among the more important objects of this invention is the provision of a receiving set which, while simple in construction and operation, and inexpensive in cost, is nevertheless capable of very sharp and quick tuning and efficient detuning.

A further object of our invention is the provision of a circuit for the reception of electric impulses at radio frequencies which is simple in character and of a hook up which is efficient in operation and inexpensive in its manufacture.

A still further object of our invention is the provision of a circuit for the reception of electric impulses at radio frequencies in which the primary is untuned so as to enable sharp tuning and increased volume.

A still further object of our invention is the provision of a circuit for the reception of electric impulses at radio frequencies in which the secondary is wound to work with a variable condenser of .0005 M. F. D. capacity.

A further object of our invention is the provision of a three circuit tuner having inductance members each one of which is in the form of a flat coil and self supporting, said coils being wound so as to put the necessary amount of wire in the least amount of space and being supported without the use of chemicals, tubing, or any other insulating material and being adapted to be mounted at an angle of 45 degrees.

A further object of the invention is the provision of a three circuit tuner having inductance members each one of which is wound in such a manner as to reduce the dielectric losses to a minimum.

A still further object of the invention is the provision of a three circuit tuner having two fixed coils mounted at an angle of 45 degrees and a movable flat coil mounted in the fixed coils, the angular displacement of the movable coil about its axis being greater

than the angular displacement of the movable coil with respect to the fixed coils.

A still further object of the invention is the provision of means whereby the movable and fixed coils or units of a three circuit tuner may be mounted upon a panel with a minimum of parts and in an efficient and durable manner.

A further object of our invention is the provision of novel mounting means that permit a compact assembly of a three circuit tuner.

A still further object of our invention is the provision of novel mounting means for a movable coil in a three circuit tuner which permit of a 180 degree angular displacement of the movable coil.

A still further object of our invention is the provision generally of a new and simplified receiving apparatus and of a new, improved and inexpensive arrangement of inductance coils therefor.

With the foregoing and other objects in view which will appear as the description proceeds, my invention consists in the construction, arrangement, and combination of parts of my device whereby the objects contemplated are attained, as hereinafter more fully set forth, pointed out in the appended claims, and illustrated in the accompanying drawings, in which:

Figure 1 is a view in side elevation of a low loss three circuit tuner mounted upon a panel in accordance with the present invention.

Figure 2 is a vertical section through the circuit tuner showing in full lines the coils in the position of maximum coupling and in dotted lines the coils in the position of minimum coupling.

Figure 3 is a front plan view looking in the direction of arrow C.

Figure 4 is a top plan view looking in the direction of arrow B.

Figure 5 is a plan view of one of the fixed coils.

Figure 6 is a development of a portion of the winding taken on line 6-6 of Figure 5.

Figure 7 is a front plan view of the movable coil illustrating the course of the wire.

Figure 8 is a view in perspective of a casting for mounting the fixed coils.

Figure 9 is a cross section of the casting shown in Figure 8.

Figure 10 is a detailed view showing the insulating eyelets used with the casting of Figure 8.

Figure 11 is a view in side elevation of the mounting means for the movable coil.

Figure 12 is a view in rear elevation of the mounting means shown in Figure 11; and

Figure 13 is a view in perspective of the mounting means of Figure 11.

Throughout the drawings like reference characters indicate like parts.

Referring to the drawings more particularly, P indicates a panel and C a casting upon which are mounted the two stationary or fixed coils S and S'.

The casting C comprises a vertical body portion 1 and a fork 2 having legs or arms 3 and 4 extending at an angle of 45 degrees from the upper end of the vertical body portion, the legs, or arms being provided with openings 5 for the reception of insulating eyelets 6. A boss or knob 7 is cast integral with the vertical body portion at its lower end. The boss or knob 7 is threaded on its outer side as at 8 for receiving the nut 9 which detachably secures the casting C to the panel P. A washer 10 is inserted between the panel P and the nut 9. A bore 11 adapted to receive a shaft 12 is drilled through the knob 7 and casting 1, the diameter of the bore through the knob being greater than its diameter through the casting, thus forming a shoulder 13 against which abuts the enlarged portion 14 of the shaft 12. A pin 15 upon the shaft 12 is adapted to engage a leaf spring 16 secured to the casting C by suitable fastening means 17 to limit the rotation of the shaft 12 and 40 to hold the shaft in any adjusted position. A dial D having a knob K is mounted on the enlarged portion 14 of the shaft for rotation of the latter.

The stationary or fixed coils S and S' are preferably in the form of flat or pancake coils the coil S being shown for purposes of illustration as the primary and the coil S' as the secondary. These coils are formed by winding the wire on a form comprising a hub and detachable spokes, the wire being wound in layers lengthwise of two spokes, then crosswise between the second and third spokes, lengthwise of the third and fourth spokes, and so on until a coil of the desired size is obtained. The spokes are then removed and the hub allowed to drop out, leaving a coil as shown in the drawings. The coil thus formed is flat, self supporting, and has a tendency to avoid any distributed capacity among the windings and allow the flow of radio frequency through the coil with the least amount of resistance while reducing dielectric losses to a minimum due to the fact that no chemicals or insulating materials are required to retain the shape

of the coils when completed. The secondary coil is wound to work with a variable condenser of .0005 M. F. D. capacity thus enabling tuning to a range of 250 to 550 meters. The coils may be wound of a single strand of wire but Litzendraht wire is preferred. If desired, strips of adhesive tape 18 may be employed to hold the coils in pancake form. The primary and secondary coils S and S' are mounted on the fork of the casting C at a 45 degree angle to panel P as shown in Figures 1 and 2 by means of suitable binding posts 19 and 20 which pass through insulating eyelets 6 and held thereon by nuts 27. The primary coil S is secured to the binding posts 19 by means of insulating strips 21 and 22 and nuts 23 and 24 as shown in Figures 2 and 3. The secondary coil S' is secured to binding posts 20 by means of insulating strips 25 and nuts 26. Binding posts 28 are attached to the lower end of the coil S by means of insulating strips 29 and 30 and nuts 31 as shown in Figure 3.

Mounted on the forward end of the shaft 12 is a circular collar 32 comprising a body 33 and a boss or knob 34 having a bore 35 drilled at a 45 degree angle to the vertical plane of the body 33 and adapted to receive the forward end of the shaft 12 which is held therein by set screw 36. The movable coil or rotor 37 is attached to the front face of the collar 32 by means of the screw 38' adapted to be inserted into threaded opening 39. The rotor or movable coil 37 is positioned in the plane of the secondary coil S' and by turning shaft 12 through knob K it can be rotated from its full line position in Fig. 2 to the dotted line position shown in the same view which position places the rotor at right angles to the primary and secondary coils. As a result of this construction, it will be noted that the movable coil has an angular displacement of 180 degrees about its own axis while moving from the plane of the secondary coil to its perpendicular position. The pin 15 limits the rotation of the rotor. The rotor being wound on a spider-web form and movable through 180 degrees permits of coupling when tuned from minimum to maximum regenerating points. By virtue of the fact that no insulating supporting material for our particular form of primary and secondary coils is employed and since the movable coil may be rotated through an angle of 180 degrees to effect movement of the rotor through an angle of 90 degrees with respect to the stationary coils, very sharp and quick tuning as well as efficient detuning may be obtained.

From the foregoing description it will be seen that we have devised a circuit for the reception of electric impulses at radio frequencies which is simple in character, effi-

cient in operation, and inexpensive in manufacture, the inductive members of which are wound so as to reduce dielectric losses to a minimum and in which the movable and 5 fixed coils may be mounted on a panel with a minimum of parts, the movable coil being capable of 180 degree angular displacement and the entire assembly and arrangement of parts permitting of sharp and quick tuning 10 as well as efficient detuning.

We would state in conclusion that while the illustrated example constitutes a practical embodiment of our invention, we do not limit ourselves strictly to exact details 15 herein illustrated since, manifestly, the same can be varied considerably without departing from the spirit of the invention as defined in the appended claims.

Having described our invention, what we 20 claim as new and desire to secure by Letters Patent of the United States is:—

1. In a device of the character described, a casting, means for securing said casting to a panel, a shaft positioned in said means, 25 self supporting, fixed, flat coils mounted on said casting, a movable coil, means for mounting said movable coil on said shaft, said means comprising a circular collar detachably secured to said shaft and positioned at an angle of 45 degrees to the shaft.
2. In a device of the character described, 30 a casting, means for securing said casting to a panel, a shaft positioned in said means,

self supporting, fixed, flat coils mounted on said casting, a movable coil, means for 35 mounting said movable coil on said shaft, said last mentioned means comprising a circular collar detachably secured to said shaft and positioned at an angle of 45 degrees to the shaft, and means for limiting 40 the rotation of said shaft and holding the same in any adjusted position.

3. In a device of the character described, a casting comprising a vertical body portion and a fork, said fork extending from the upper end of said body portion and inclined thereto, a boss on the lower part of said vertical portion, screw threads on the outer surface of said boss, and a bore extending through said boss and body portion, the diameter of the bore through the boss being greater than the diameter of the bore 45 through the body portion.

4. In a device of the character described, a collar comprising a circular body portion, 55 a knob extending from the rear face of said body portion, a bore drilled at an angle of 45 degrees to the body portion extending through said knob, a set screw positioned in said knob, and a screw threaded opening in 60 the front face of said body portion.

In testimony whereof we affix our signatures.

BENJAMIN W. SUCKLE.
THOMAS J. MATHEWS.
